UNITED STATES PATENT OFFICE.

WEBSTER C. ESTES, OF BROOKLYN, NEW YORK.

DESIGN FOR A BOX.

SPECIFICATION forming part of Design No. 26,971, dated April 27, 1897.

Application filed March 15, 1897. Serial No. 627,695. Term of patent 14 years.

To all whom it may concern:

Be it known that I, WEBSTER C. ESTES, a citizen of the United States, residing at Brooklyn, in the county of Kings and State of New York, have invented and produced a new and original Design for a Wooden Box, of which the following is a specification, reference being had to the accompanying drawings, in which—

10 Figure 1 is a vertical section; Fig. 2, a plan, and Fig. 3 an elevation with the parts of the box shown separately.

The general configuration of the wooden box is round, and the leading features consist 15 of the ribbed and coved base to the body, the dome-shaped cover, and the ribbed conical stopper.

The design of the body A comprises the parallel sides *a*, the ribs *b* *c*, the cove *d*, and the 20 bands 2 3 in a group at the lower end of the body A and the upper rib *e*.

The design of the cover B comprises the sides *a'*, which are continuations of the sides *a* of the body of the box, the dome-shaped top *f*, and the rib *h* between said sides *a'* and 25 said dome-shaped top *f*.

The design of the stopper C comprises the rib *i*, the conical upper end *k*, and the under curved contracted portion *l*.

My new and original wooden box is adapted 30 for use with toilet and similar powders.

What I claim is—

The design for a wooden box substantially as shown and described.

Signed by me this 11th day of March, A. D. 35 1897.

WEBSTER C. ESTES.
